UNITED STATES PATENT OFFICE.

CHARLES A. TUCKER, OF BROOKLYN, NEW YORK.

DESIGN FOR A NECKTIE-HOLDER.

SPECIFICATION forming part of Design No. 24,863, dated November 5, 1895.

Application filed September 17, 1895. Serial No. 562,805. Term of patent 7 years.

To all whom it may concern:

Be it known that I, CHARLES A. TUCKER, a citizen of the United States, residing at Brooklyn, in the county of Kings and State of New York, have invented and produced a new and original Design for a Necktie-Holder, of which the following is a specification, reference being had to the accompanying drawings, forming a part thereof, in which—

Figure 1 is a front elevation of the holder, and Fig. 2 is a bottom plan view thereof.

The leading feature of the design consists in a body member A and a head member B, both of which members are of loop form, the head member B being of less size and apparently centrally placed on the body member.

The body member A is shaped as an elongated

ated loop and is tapered in direction of its ends, and the said body member is also longitudinally curved, as shown in Fig. 2, being 20 concaved on one face and convexed upon the opposing face.

The head member B represents, approximately, a circular loop, and is apparently independent of the body member, yet carried 25 thereby. The body member has a flattened facial appearance.

I claim—

The design for a neck-tie holder, substantially as herein shown and described.

CHARLES A. TUCKER.
